UNITED STATES PATENT OFFICE.

JEREMIAH J. DICKSON, OF INDIANAPOLIS, INDIANA.

FENCING-FASTENER FOR FENCE-POSTS.

No. 895,981.

Specification of Letters Patent.

Patented Aug. 11, 1908.

Application filed March 25, 1908. Serial No. 423,127.

To all whom it may concern:

Be it known that I, JEREMIAH J. DICKSON, a citizen of the United States, residing at Indianapolis, in the county of Marion and State 5 of Indiana, have invented certain new and useful Improvements in Fencing-Fasteners for Fence-Posts; and I do declare the following to be a full, clear, and exact description of the invention, reference being had to the 10 accompanying drawings, and to the letters and figures of reference marked thereon, which form a part of this specification.

This invention relates to concrete fence posts or those that are composed of plastic 15 material, and it relates also to similar posts, the invention having reference particularly to devices whereby fencing may be fastened to the posts.

Objects of the invention are to provide im- 20 proved fence fasteners adapted to be anchored in molded posts of various substances, and to provide fencing fasteners that will permit of the removal of the fencing from the posts when repairs or renewals of the fencing 25 may be required; a still further object being to provide strong, durable and economical fencing fasteners for concrete fence posts.

With the above-mentioned and minor ob- 30 jects in view the invention consists in an im- proved fencing fastener comprising a wire- holder having a shank adapted to be anchored in the body of the post, the holder having a slot in the side thereof to receive a fence wire and provided with a collar for 35 retaining the wire in the slot, the holder being provided with a key for fastening the collar to the holder; and the invention consists further in the novel parts and combinations and arrangements of parts, as herein- 40 after particularly described and defined in the appended claims.

Referring to the drawings Figure 1 is a front elevation of a fence post having the improved fencing fasteners applied thereto, 45 fragments of fencing wires being connected to the post by the fasteners; Fig. 2, a vertical central sectional view of a portion of the post and fasteners mounted therein; Fig. 3, a horizontal sectional view of the post and 50 taken centrally of one of the fasteners; Fig. 4, a perspective view of the key forming a part of the fastener; Fig. 5, a side view of the collar forming a part of the fastener; Fig. 6, a side view of the wire holder and shank; Fig. 7, a front elevation of the collar; and 55 Fig. 8, a front elevation of the wire holder.

Similar reference characters in the several figures of the drawings designate like parts or features of the construction.

The post body *a* may be formed of any 60 suitable material but preferably of sand, gravel and cement mixed with water and shaped in molds while in the plastic state. The fencing may comprise cable wires *b* or single wires *c* as may be preferred or desired. 65 Any desired number of the improved fasteners may be applied to a post while being molded or otherwise formed.

Each fencing fastener comprises a wire holder *d* that is shaped externally somewhat 70 like the frustum of the cone, the larger end of which has an integral shank *d'* projecting therefrom, the end of the shank having a transverse hole *e* therein, and the shanks are 75 embedded in the body of the post, a reinforcing rod *f* being also embedded in the body of the post and extending through the holes *e* to securely lock the shanks in the post body. The wire-holder has a slot *g* in the upper portion thereof that extends from 80 the surface of the holder downward and inward toward the large end of the holder, the bottom of the slot forming a wire seat *g'* to support a horizontal fencing wire. The 85 smaller portion or outer end of the holder has a vertical slot or key-way *h* therein.

In order to lock the fencing wire in the holder a collar *i* is provided that is conical in shape so as to fit over the exterior of the wire-holder, and the collar has semi-circular 90 notches *j* and *j'* in the wall of the large end thereof to receive portions of the fence wire and prevent the wire from being withdrawn laterally from the slot *g*. The proportion may be such that the fence wire may be 95 clamped tightly by means of the collar, or the collar may fit closely on the wire-holder while permitting the fence wire to move longitudinally on the seat *g'*. The smaller end of the collar preferably has slots *k* and *k'* 100 in the end face thereof. A taper key *l* is formed of suitable metal and is inserted in the slot or key-way *h* and in the slots *k* and *k'* and may be driven tightly so as to force the collar tightly either against the fence 105 wire or onto the wire-holder, as may be pre-arranged. Preferably the wire-holder has a flange *m* extending around the large portion thereof to form a substantial bearing in the post body. The body of the post may be 110 reinforced in any suitable or desired manner, as is customary.

In practical use the keys *l* and the collars *i* should be removed from the main portion of the fasteners and then the fencing wires may be placed on the seats *g'*, after which the 5 collars may be applied and then secured by means of the keys, and it will be obvious that the wires may be readily removed from the fasteners and replaced should occasion require it.

10 Having described the invention, what is claimed as new is—

1. A fencing fastener comprising a conical wire-holder having a slot in the side thereof and having also a keyway in the smaller 15 portion thereof, a collar on the holder and extending partially over the slot, and a key inserted removably in the keyway and securing the collar removably on the holder.

2. A fencing fastener comprising a conical 20 wire-holder having an integral shank for its support, the shank having an aperture therein, said holder having a slot in the side thereof and having also a key-way in the smaller portion thereof, a collar on the holder and 25 extending partially over the slot, the collar having notches in the wall of the larger end thereof registering with the bottom of the slot, and a key insertible in or removable from the key-way for securing the collar on 30 the holder.

3. In a fence post, the combination of a concrete body, a plurality of fence fasteners having apertured shanks embedded in the concrete body and having also slots in the upper portions thereof and collars thereon 35 extending partially over the slots, a reinforcing rod embedded in the concrete body and extending through the apertures of the plurality of shanks, fencing wires seated in the slots of the holders and engaged by the 40 collars, and means securing the collars on the holders.

4. In a fencing fastener, a wire-holder having a conical exterior, the larger end of the wire-holder having an integral shank 45 thereon, said wire-holder having a slot in the side thereof extending obliquely inward and toward the larger end thereof, said wire-holder having also a keyway in the smaller end thereof near said slot, in combination 50 with a collar fitting removably on said wire-holder, and a key fitting removably in said keyway.

In testimony whereof I affix my signature in presence of two witnesses.

JEREMIAH J. DICKSON.
